UNITED STATES PATENT OFFICE.

ALBERT WILLIAM HARRIS, OF GLENS FALLS, NEW YORK.

SEAM FOR WOVEN-WIRE FABRICS.

Application filed June 16, 1924. Serial No. 720,415.

To all whom it may concern:

Be it known that I, ALBERT WILLIAM HARRIS, a citizen of the United States of America, and resident of Glens Falls, county 5 of Warren, in the State of New York, United States of America, have invented certain new and useful Improvements in Seams for Woven-Wire Fabrics, of which the following is a specification.

10 This invention relates to improvements in seams for woven wire fabric, such as are used on endless woven wire belts used in paper-making machines, and the objects of the invention are to provide for better drainage of the belt or fabric at the seam, to enable shorter stitches to be used and thus avoid the risk of stitches getting out of place and in consequence being destroyed, and to enable the pull on the closing wire 15 of the seam to be transmitted back to the interior lay wires thereof.

Further objects of the invention are to enable a firm joint to be obtained with as great simplicity and ease of construction as 25 possible.

Further objects still are to obtain extreme durability and generally to better adapt it to perform the functions required of it.

30 The invention consists essentially of the improved construction hereinafter described in detail in the accompanying specification and drawings, and in which a single wire serves both as a whipping wire and as a 35 closing wire, as more particularly pointed out hereinafter.

Figure 1 is a plan view of an embodiment of my invention, drawn to an enlarged scale.

Fig. 2 is a side view of the seam, showing 40 the lay wires in section.

Fig. 3 is a plan view of an alternative embodiment of the invention.

Fig. 4 is a sectional elevation of the arrangement shown in Fig. 3.

45 Fig. 5 is a plan view of another embodiment of the invention.

Fig. 6 is a sectional elevation of the embodiment shown in Fig. 5.

Fig. 7 is a plan view of another embodiment 50 of the invention.

Fig. 8 is a sectional elevation of the embodiment shown in Fig. 7.

Fig. 9 is a plan view of another embodiment of the invention.

55 Fig. 10 is a sectional elevation of the embodiment shown in Fig. 9.

Fig. 11 is a cross-section taken parallel to one of the lay wires in Fig. 9 and showing the arrangement of the warp wires with respect thereto, the construction being the same in cross-section for all the figures except Fig. 12.

Fig. 12 is a plan view of an alternative embodiment of the invention.

Fig. 13 is a sectional view of the form 65 shown in Fig. 12.

Fig. 14 is a cross-section taken parallel to one of the lay wires in Fig. 12.

Fig. 15 is a plan view of an alternative 70 form of the invention.

Fig. 16 is a sectional view through the form shown in Fig. 15 and taken parallel to the warp wires.

All of the drawings are made to an enlarged scale to more fully illustrate the construction, and in the drawings like characters of reference indicate corresponding parts in each figure.

Referring to the drawings generally, A and B indicate two sections of the woven 80 wire fabric which are to be joined by the seam, the fabric itself comprising a plurality of parallel lay wires 10 and a plurality of longitudinally extending and parallel warp wires 11. The fabric itself, in each of the embodiments illustrated, is of well-known designs not forming part of the present invention. The plan views of the drawings, in each instance, show the side of the fabric which runs next the paper machine.

Referring now particularly to the form of fabric shown in Fig. 1, 12 indicates a whipping wire, which also constitutes a closing wire, the said whipping wire, on the 95 side next to the paper machine, extending over 3 lay wires on the part B, and 1 lay wire on the part A therein and diagonally under the upper side, being bent to avoid the knuckles in the fabric as indicated. On 100 the side A of the seam an ordinary whipping wire 13 is provided, which binds the first lay wire 14 to the third and fourth lay wires, the stitches alternately covering 3 and 4 lay wires as indicated.

To give additional strength, the warp wires 11 on the part B are preferably soldered to the end lay wire 15, soldering material 16 being indicated by double lines in Fig. 1. The ends of the warp wires are 110 in this way firmly held in their correct positions and the warp wires, therefore,

tend to hold the second and third lay wires in their positions. In this way the working tension of the whole fabric is prevented from causing the stitching wire to pull the 5 lay wires out of place and in this way from pulling the fabric apart. As shown, only the lay wires on the side B immediately adjacent to the opening have been soldered, but if desired the second lay wire could be 10 soldered in place of the first, or both the first and second lay wires could be soldered.

If the lay wire is not soldered as indicated, it may be necessary to go over an increased number of lay wires, say 4 instead of 3.

It will be seen that the stitches of the combined whipping and closing wire 12 extend over 3 lay wires on the part B and 1 lay wire on the part A. In the form 20 illustrated in Fig. 1, the solder is omitted from the side A; but it could also be used on that side if desired.

It would be obvious that the ratio of the 25 number of stitches to meshes may be varied. While I have shown the stitches in the ratio of 1 to 2, other ratios such as 1 to 3, 2 to 3, or 3 to 5, may be used.

The form of fabric, illustrated in Fig. 1, is of a special form in which the warp 30 wires are provided with long knuckles 17 on one side and with short knuckles 18 on the opposite side.

The length of the stitches of the combined whipping and closing wire 12 may be 35 varied, and in Figs. 3 and 4 I have shown a whipping and closing wire 12^a which extends over 2 lay wires on the part A.

In the alternative form of the invention 40 shown in Figs. 3 and 4, 12^a indicates the whipping and closing wire, which extends over 2 lay wires on the part A and 1 lay wire on the part B. The part B has the ordinary whipping wire 13^a, the stitches of which extend alternately over 3 and 4 lay 45 wires. The end lay wire 15^a, on the part A is shown soldered to the warp wires 11. The whipping wires are always so placed that they pass to one side of the knuckles and never over them.

50 The alternative form of the invention, shown in Figs. 5 and 6, is not a form of interlooped seam, the whipping and closing wire 12^b not looping through the whipping wire 13^b. In this form of the invention, the whipping and closing wire 12^b covers 55 2 lay wires on the part B and the end lay wire on the part A, while 13^b covers 3 lay wires. No solder is shown in this form of the invention. The whipping and closing 60 wire 12^b and the whipping wire 13^b are shown with the ratio of stitches to number of meshes in the proportion of 1 to 3.

The alternative form of the invention, 65 shown in Figs. 7 and 8, shows an interlooped form, in which the loops of the

stitches in the combined whipping and closing wire 12^c are threaded through the loops of the stitches in the whipping wire 13^c, each of the whipping wires covering 3 lay wires. In the case of the whipping wire 70 12^c, 2 of the lay wires which it covers are on the part B, while one is on the part A.

The alternative form of the invention, 75 shown in Figs. 9 and 10, shows the whipping wires formed on the paper side with both straight and inclined portions. In this form of the invention, the whipping and closing wire 12^d extends over 2 lay wires on the part A and the end lay wire on the part B. The whipping wire 13^d, on 80 the part B, extends over the 3 end lay wires, and in each instance the portions of the whipping wires 12^d and 13^d, adjacent the seam opening, extend substantially parallel with the warp wires.

The alternative form of the invention 85 shown in Figs. 12 and 13, illustrates a seam as applied to a plain weave. The whipping and closing wire 12^e extends over 2 lay wires on the part A and the end lay 90 wire on the part B, while the whipping wire 13^e extends over 3 lay wires on the part B.

In these views the end of the part A is 95 soldered, as indicated, the soldering joining the ends of the warp wires to the end lay wire. In this form it may be observed that since the fabric illustrated has no long 100 knuckles no especially weak points are developed, but the solder is applied to hold all of the warp knuckles at the end lay wire in place and in this way prevent the seam pulling apart where the whipping wires go around the second and third lay wires on parts A and B respectively. Variations in length and arrangement of 105 stitches may be made to suit requirements.

It will be observed that, wherever possible, the stitches of the seam, on the side of the wire which runs next to the paper machine, are made parallel to the warp wires. Thus in the case of seams which are made with a ratio of 1 stitch to 2 meshes, and the sewing wires of which do not loop through the opposite whipping wire, the stitches may be on the side next to the machine approximately parallel to the warp wires so that they never go across the knuckles, or if for part or all of their length they are diagonally inclined to the 110 warp wires such a condition will always occur in such a way that the stitches pass between the knuckle and not over them. Generally speaking, in all of the seams the 115 stitches go between the knuckles and never across them.

In the case of seams which are made with a ratio of 1 stitch to 2 meshes and which have the sewing or closing wire 120 looped through the whipping wire loops, 125

the whipping wire stitches are on the machine side of the wire diagonally inclined to the sewing wire stitches and to the warp wires, thus distributing the stitches more evenly than would otherwise be the case and so giving more uniform drainage. (See Fig. 7.) On the side next to the paper, it is the sewing or closing wire stitches which are inclined.

10 In the case of seams with the ratio of 1 to 3, the sewing wire stitches and whipping wire stitches are generally speaking both inclined to the warp wires on both sides of the fabric. But wherever possible, part of their 15 length has been made parallel to the warp wires. (See Fig. 5.)

When matching the two ends of the cloth to be united these may be so cut and placed that a long knuckle may be opposite a long 20 knuckle or a short knuckle opposite a long knuckle, dependent upon the ratio of number of stitches to meshes and length and variations of stitches. Length and variations of 25 stitches may obviously be made to suit requirements.

In the alternative form of the invention, shown in Figs. 15 and 16, the whipping and closing wire 12' and whipping wire 13' are shown with the ratio of stitches to the number of meshes in the proportion of 2 to 3. It will be seen that the stitches of 12' cover 30 3 of the lay wires on the side B of the seam and the end lay wire on the side A. The number of warp wires between the stitches 35 of the whipping and closing wire 12' are alternately 1 and 2. The whipping wire 13' is formed with stitches alternately including 3 and 4 lay wires, the stitches being separated alternately by 1 and 2 warp wires.

As many changes could be made in the 40 above construction and many widely different embodiments of my invention, within the scope of the claims, constructed without departing from the spirit or scope thereof, it is intended that all matter contained in 45 the accompanying specification and drawings shall be interpreted as illustrative and not in a limiting sense.

What I claim as my invention is:

1. A seam for woven wire fabrics wherein the seam combines warp wires and lay wires comprising a combined whipping and closing wire covering a plurality of lay wires and extending beneath a plurality of lay wires on one side of the seam and over 50 one lay wire on the opposite side of the seam and a whipping wire on said opposite side of the seam extending over a plurality of lay wires and under a plurality of lay and warp wires. 55

2. A seam for woven wire fabrics wherein the seam combines warp wires and lay wires comprising a combined whipping and closing wire extending over a plurality of lay wires and then diagonally beneath the plurality of lay wires on one side of the seam and over one lay wire on the opposite side of the seam and a whipping wire on said opposite side of the seam extending over a 60 plurality of lay wires and then diagonally 65 beneath the plurality of lay wires therein. 70

In witness whereof I have hereunto set my hand in the presence of two witnesses.

ALBERT WILLIAM HARRIS.

Witnesses:

ELLA F. CLARK,
L. RAY LEWIS.
